UNITED STATES PATENT OFFICE.

WILLIAM J. SULLIVAN, OF NEW BROOKLAND, SOUTH CAROLINA

AUTOMATIC BALL-BEARING BOBBIN-HOLDER.

1,231,217.

Specification of Letters Patent. Patented June 26, 1917.

Application filed September 7, 1915. Serial No. 49,884.

To all whom it may concern:

Be it known that I, WILLIAM J. SULLIVAN, a citizen of the United States, residing at New Brookland, in the county of Lexington, in the State of South Carolina, have invented a new and useful Automatic Ball-Bearing Bobbin-Holder, of which the following is a description and specification.

The object of my invention is to provide 10 an improved method for holding a threaded bobbin on a spinning frame so as to allow the thread on the bobbin to unwind slowly and automatically as it is being used by the spinning machine.

15 The object of my invention is attained by the mechanism illustrated in the accompanying drawing.

Figure 1. of the drawing is a front elevation of the automatic ball bearing bobbin holder; Fig. 2. is an end view of the same; Fig. 3. is a longitudinal sectional view through the holder; Fig. 4. is transverse sectional view showing the base F G H on which the bottom of the bobbin fits; Fig. 5. 20 is a longitudinal sectional view of the base holder F G H showing the ball bearings I; Fig. 6. is a detail top view of the base holder showing the ball bearings I and cup G and key F on which the bottom of the bobbin 25 fits; Fig. 7. shows a spring E provided with a knob K attached adapted to be inserted in the upper end of the bobbin; Fig. 8. represents a plan view of the same.

Similar letters refer to similar parts 30 throughout the several views.

The base A (Fig. 1.), its standards B B, and the horizontal cross bar C constitute the frame work of the bobbin holder. D represents the threaded bobbin in the holder. 40 G is the circular cup over which the bottom of the bobbin fits; F is the key on the side of the cup over which key the cut out section on the bottom of the bobbin fits. H is the base of the bobbin holder in which are contained ball bearings as shown by I in Fig. 6. The top of the base H surrounding and overlapping the outer edge of the disk-like base 45 of the cup G, thus providing means to hold the cup G properly positioned upon the ball bearings I. On the bottom side of the horizontal bar C (Fig. 1.) is fastened a flat

spring E, at one end of which, and on its lower side, is attached a round knob K designed to fit loosely in the top of a bobbin. The knob K is immediately above the cup 55 G, so that when the bobbin D is in the bobbin holder, it is in an upright position as indicated by D in Fig. 1.

The operation of my invention is as follows:

The bobbin D filled with thread rests in the automatic ball bearing bobbin holder as above set forth. See D Fig. 1. The end of the thread on bobbin D is attached to the spinning machine. The operation of the 60 spinning machine pulls the thread, and it is necessary for it to unwind slowly and evenly from the bobbin D. The cut out section in the bottom of the bobbin D fits over the key F as above set forth. See 65 F G Fig. 1. The pulling of the thread by the operation of the spinning machine thus causes the cup G to rotate on the ball bearings I beneath. The key F causes the bobbin D to rotate with the cup G on 70 which the bobbin rests. By means of the ball bearings I, the unwinding of the thread is made even and steady and the danger of the thread breaking is eliminated. When the thread on the bobbin becomes 75 exhausted, the operator takes hold of the empty bobbin D with one hand, pushes it upward against the spring E attached to the cross bar C and pulls the bottom of the bobbin D outward and it is released from 80 the base. Thus the empty bobbin is released from the holder, and the operator puts in 85 its place a threaded bobbin. The loose end of the thread on the threaded bobbin is attached to the thread on the spinning machine, and the process of feeding the thread 90 to the machine continues. Thus the use of the automatic ball bearing bobbin holder renders the bobbin stick useless, causes the spinning machine to be fed with thread uniformly, and prevents the frequent breaking 95 of the thread.

I claim:

A bobbin holder comprising a base plate having an annular ball receiving groove, 100 ball bearings in said groove, a bobbin supporting member rotatably mounted upon

said ball bearings and having a cylindrical extension adapted to enter and position the base of a bobbin upon said member, said base plate having an annular extension sur-
5 rounding and overlapping the outer edge of the bobbin supporting member to retain the same in position, and a key mounted upon

said supporting member adapted to form a driving engagement between the bobbin and supporting member.

WILLIAM J. SULLIVAN.
